United States Patent Office

Des. 178,191
Patented July 3, 1956

178,191

CHAIR

Gorden Larsen, Menominee, Mich., assignor to Heywood-Wakefield Company, Gardner, Mass., a corporation of Massachusetts

Application August 8, 1955, Serial No. 37,343

Term of patent 7 years

(Cl. D15—1)

Fig. 1 is a front perspective view of a chair showing my new design; and

Fig. 2 is a rear perspective view of a chair showing my new design.

The dominant features of the design reside in the portions shown in full lines.

I claim:

The ornamental design for a chair, substantially as shown and described.
